Patented Aug. 24, 1920.

UNITED STATES PATENT OFFICE.

IRA D. BRILL, OF MARLINGTON, WEST VIRGINIA.

LOCK.

1,350,356.

Specification of Letters Patent. Patented Aug. 24, 1920.

Application filed February 28, 1920. Serial No. 361,974.

To all whom it may concern:

Be it known that I, IRA D. BRILL, a citizen of the United States, residing at Marlinton, in the county of Pocahontas and State of 5 West Virginia, have invented a new and useful Lock, of which the following is a specification.

The device forming the subject matter of this application is a lock, and one object of 10 the invention is to provide a structure of the sort alluded to which may be mounted readily in a door or other barrier, it being necessary merely to bore a hole in the edge of the door, and to bore a hole transversely 15 through the door.

The invention aims to provide a lock which may be manipulated readily from the inside of the door, through the instrumentality of a knob, it being possible to manipulate 20 the device from the outside of the door, by means of a knob, only after a key has been inserted into the outside knob.

A further object of the invention is to provide a lock which will be compact in 25 construction, embodying but few parts.

The invention aims to provide novel means for moving the locking bolt.

It is within the province of the disclosure to improve generally, and to enhance the 30 utility of devices of that type to which the invention appertains.

With the above and other objects in view, which will appear as the description proceeds, the invention resides in the combination 35 and arrangement of parts and in the details of construction hereinafter described and claimed, it being understood that, within the scope of what is claimed, changes in the precise embodiment of the invention 40 shown can be made without departing from the spirit of the invention.

In the accompanying drawings:—

Figure 1 is a horizontal section, taken through a door wherein the device forming 45 the subject matter of this application has been mounted, parts appearing in elevation; Fig. 2 is a vertical section taken approximately on the line 2—2 of Fig. 1, parts having been left in elevation; Fig. 3 is a cross 50 section taken through the casing of the lock, on the line 3—3 of Fig. 2; Fig. 4 is a fragmental vertical section taken on the line 4—4 of Fig. 3, parts being in elevation; Fig. 5 is a transverse section taken on the line 5—5 55 of Fig. 4; Fig. 6 is a cross section on the

line 6—6 of Fig. 1; and Fig. 7 is a cross section on the line 7—7 of Fig. 1.

The numeral 1 denotes a barrier of any sort, such as a door, a recess 2 being formed in the free edge of the door. This recess 2 60 ordinarily is fashioned by boring a hole with an auger or like tool in the edge of the door 1. A transverse hole is bored through the door 1, thereby forming side openings 3 which communicate with the recess 2. From 65 the foregoing it will be obvious that, so far as preparing the door for the reception of the lock is concerned, it is necessary merely to bore one auger hole into the edge of the door 1 and to bore another auger hole 70 through the door from side to side.

A tubular casing 4 is mounted in the recess 2 and is held in place by a plate 5 cooperating with the forward or free edge of the door 1. The plate 5 may be held in 75 place in any suitable way, and as the tastes of the manufacturer may demand. The tubular casing 4 is provided, as shown best in Fig. 1, with side openings 6, aligned with the side openings 3 in the door 1. 80

A frame is fixed within the tubular casing 4, the frame being a composite structure and including a disk 7 secured within the casing 4 immediately in the rear of the side openings 3, the frame including a disk 8 disposed 85 immediately in front of the openings 6, a disk 9 being secured in the casing 4 between the disk 8 and the outer end of the casing. For convenience in claiming the invention, or in describing it briefly hereinafter, the 90 disks 7, 8 and 9 may be alluded to as supports. Rods 10 extend longitudinally of the casing 4 and connect the disks or supports 9 and 8. The disks 8 and 7 are connected by 95 similar rods 11.

The numeral 12 designates generally, a locking bolt embodying a head 14 mounted to slide in the plate 5 and fitting closely but slidably in the forward end of the casing 4, the head having a rearwardly projecting 100 tubular stem 15 mounted to reciprocate in the forward disk 9. The rear end of a spindle 16 is secured to the intermediate disk 8, the forward end of the spindle 16 projecting through the forward disk 9, the rear end 105 of the stem 15 of the locking bolt 12 being slidably mounted upon the forward end of the spindle. A cross head 17, shown in outline in Fig. 5, is secured to the rear end of the tubular stem 15 of the locking bolt 12 110

and is disposed behind the disk 9, the cross head being provided in its ends with notches or openings 19, the function of which will be made manifest hereinafter. A compression spring 18 surrounds a portion of the spindle 16, the rear end of the spring abutting against the disk 8, the forward end of the spring abutting against the cross head 17, or, at least, against the rear end of the tubular stem 15 of the locking bolt 12. Recalling that the frame comprising the disks 9 and 8 is fixed within the tubular casing 4, it will be clear that the spring 18 tends to advance the locking bolt 12 until the cross head 17 engages the forward disk 9, the parts being shown thus arranged in Fig. 1 of the drawing.

The numeral 20 denotes a pair of slides located within the casing 4 and diametrically opposite to each other, the slides being in the form of bars having racks 21 on their inner edges, intermediate the ends of the slides. The slides are mounted for right line reciprocation in the edges of the disks 7 and 8, the slides being received in the notches 19 of the cross head 17. Upon their outer edges, the slides 20 are shaped, as shown at 22 in Fig. 3, to coöperate with the inner surface of the tubular casing 4 in such a way that the slides cannot rotate upon their axes. Consequently, the racks 21 always project inwardly. Since the slides 20 are received in the notches 19 of the cross head 17, the cross head cannot tilt and the locking bolt 12 cannot rotate on its axis, the bevel 100 of the head 14 of the locking bolt being kept always in such a position that it will exercise its function when the door 1 is swung to a closed position. The forward ends of the slides 20 are supplied with lateral lugs 23, shown best in Figs. 3 and 4. There are openings 24 (see Fig. 3) in the forward disk 9, the openings being so shaped and being large enough, so that the lugs 23 can pass therethrough, when the sides 20 are drawn rearwardly. The lugs 23, having passed through the openings 24 in the forward disk 9, coöperate with the cross head 17, so as to draw the cross head and the locking bolt 12 rearwardly, thereby compressing the spring 18, it being observed at this point, referring to Fig. 5, that the notches 19 in the cross head 17 are not large enough to permit the lugs 23 to pass therethrough when the slides 20 are drawn rearwardly, a comparison of the notches 19 of Fig. 5 with the openings 24 of Fig. 3 being profitable at this point. The rear end of the head 14 of the locking bolt 12 may be cut away as shown at 25, so as to receive the lugs 23 on the slides 20, when the slides are advanced.

It has been pointed out hereinbefore that a right line reciprocation is imparted to the slides 20, the means for imparting this reciprocation to the slides embodying a pinion

26 located within the casing 4 and engaging the racks 21 of the slides 20, as shown in Fig. 2 of the drawings. The pinion 26 is carried by a shaft 27 mounted to rotate in a face plate 28, secured to the inner side of the door 1, the inner end of the shaft 27 being provided with a knob 29.

In that side of the pinion 26 which is remote from the knob 29, a circular opening 30 is fashioned, there being lateral seats 31 in the pinion, the seats communicating with the opening 30, these details appearing to best advantage in Fig. 2. A face plate 32 is attached to the outer side of the door 1, a tubular spindle 33 being fixed to the plate. The numeral 34 denotes the base of a knob 35, the base of the knob having a tubular neck 36. The outer end of the tubular spindle 33 is reduced as shown at 37, so as to fit within the neck 36 of the knob 35. Screws 38 or like securing devices are mounted in the neck 36 of the knob 35, the inner ends of the screws being received in a shallow circumscribing groove 50 formed on the outer surface of the reduced part 37 of the tubular spindle 33. It will be obvious that the knob 35 thus is mounted to rotate on the spindle 33.

The numeral 39 designates a shaft located within the tubular spindle 33, the inner end of the shaft extending through one of the side openings 3 of the door 1 and through the corresponding opening 6 of the tubular casing 4, the inner end of the shaft 39 being freely rotatable in the opening 30 (see Fig. 2) which is fashioned in one side of the pinion 26. The outer end of the shaft 39 is supplied with a transverse head 40 received in grooves 41 fashioned in the neck 36 of the knob 35, the reduced part 37 of the spindle 33 serving to hold the head 40 in the grooves 41. It will now be obvious that when rotation is imparted to the knob 35, the shaft 39 will be rotated also, but, so far as the device has been described up to this point, the shaft 39 will not impart rotation to the pinion 26 because the inner end of the shaft 39 is free to rotate in the opening 30 in the side of the pinion. A slot or opening 42 is formed in the head 40 of the shaft 39 (see Fig. 7). The slot 42 extends inwardly, the full length of the shaft 39, and thus divides the shaft, inwardly of the head 40, into two parts 45 (see Fig. 6) which are approximately semi-circular in cross section. There is a slot or opening 43 in the base 34 of the knob 35, this slot corresponding in shape to the slot 42 in the transverse head 40 of the shaft 39. The numeral 44 denotes a key, the shank of which may be inserted through the slot 43 through the slot 42, and longitudinally of the shaft 39, between the parts 45 thereof, the inner end of the key 44 being received in the lateral seats 31 of the pinion 26 (see Fig. 2). When the key 130

44 is mounted in place as above described, the shaft 39 is coupled to the pinion 26 so that when rotation is imparted to the shaft, rotation will be imparted to the pinion, the 5 pinion coöperating with the racks 21 to operate the slides 20, one slide being retracted when the other slide is advanced, depending upon the direction in which the knob 35 is rotated. To the base 34 of the knob 35, a 10 shell 46 is hinged as shown at 47. The shell 46 carries a resilient latch 48, the head 49 of which is adapted to coöperate with a projection 50 on the base 34 of the knob 35, to hold the shell 46 in closed position. One 15 end of a spring tongue 51 is secured to the base 34 of the knob 35, the other end of the tongue engaging the head 49 of the latch 48, the tongue including a button 52 projecting outwardly through the base 34 of the knob. 20 When the spring tongue 51 is pushed inwardly by pressure applied to the button 52, the head 49 of the latch 48 is disengaged from the projection 50 and then the shell 46 may be swung to an open position on the 25 hinge 47.

In practical operation, a person standing on the indoor side of the door 1 may rotate the shaft 27 through the instrumentality of the knob 29. Since the shaft 27 is permanently connected to the pinion 26, the door may be opened from the inside without the use of a key, the pinion coöperating with the racks 21 of the slides 20, to retract one slide and to advance the other, depending upon the direction in which the shaft 27 is rotated. When one of the slides 20 is moved rearwardly, as above described, the projections or lugs 23 on the forward end of that slide pass rearwardly through 30 the corresponding opening 24 in the forward disk 9 and engage the cross head 17, the cross head 17 being drawn rearwardly on that slide 20 which has been advanced. When the cross head is drawn rearwardly, 35 the bolt 12 is drawn rearwardly, because the cross head is attached to the rear end of the stem 15 of the bolt, the spring 18 being compressed. Obviously, when the bolt 12 is retracted, the door 1 may be opened. 40 When the knob 29 is released, the spring 18 reacts on the cross head 17 and advances the same until the cross head engages the disk 9, the bolt 12 being advanced.

Passing now to the condition which exists when a person standing on the outside 45 of the door 1 desires to operate the bolt 12, it may be stated that if the key 44 is not in place, the knob 35 may be rotated without actuating the pinion 26 and without retracting the bolt 12, since the inner end of

the shaft 39 is freely rotatable in the opening 30 in the side of the pinion 26. When, however, the key 44 is in place, as above described, the inner end of the key is received in the seats 31 of the pinion 26. Then, if 65 the knob 35 is rotated, the pinion 26 will be rotated, and the slides 20 will be operated, the bolt 12 being retracted. If desired, the shell 36 of the knob 35 may be swung to an open position and the key 44 may be 70 withdrawn, or, if desired, the key 44 may be left in place, as shown in Fig. 1 of the drawings, under which circumstances, the knob 35 will remain operatively coupled to 75 the pinion 26.

Having thus described the invention, what is claimed is:—

1. In a device of the class described, a barrier; a bolt slidable therein; an inner knob shaft journaled in the barrier; a pinion carried by the inner knob shaft; an outer knob shaft journaled in the barrier and in the pinion; a key insertible into the outer knob shaft and constituting mechanism for connecting the outer knob shaft with the pinion; oppositely disposed slides mounted for reciprocation in the barrier and having racks coöperating with the pinion; and interengaging elements on the slides and on the bolt whereby either slide may retract 90 the bolt when said slide is retracted.

2. In a device of the class described, a barrier; a casing therein; first and second supports in the casing; a locking bolt including a tubular stem slidable in the first support; a cross head carried by the stem and located to the rear of the first support; a spindle fixed to the second support, the stem of the bolt being slidably mounted on the spindle; a compression spring interposed between the stem of the bolt and the second support; rack bars slidable in the supports, the rack bars having projections adapted to engage the cross head, the first support having openings through which the projections may pass; a pinion meshing into both rack bars; an inner knob spindle connected to the pinion; an outer knob spindle rotatable in the pinion; and a key insertible into the outer knob spindle, the key constituting mechanism for connecting the outer knob shaft to the pinion. 105 110

In testimony that I claim the foregoing as my own, I have hereto affixed my signature in the presence of two witnesses.

IRA D. BRILL.
